TOOL FOR APPLYING SEAL CAPS

John W. Shera, Chicago, Ill., assignor to American Flange & Manufacturing Co. Inc., New York, N. Y., a corporation of Illinois

Application July 1, 1936, Serial No. 88,308

8 Claims. (Cl. 113—18)

My invention relates to a tool for applying seal caps, and it has to do particularly with a tool of the foregoing character adapted for applying seal caps over the beaded end of a flange or neck defining an opening in the wall of the container.

One of the objects of my invention is to provide an improved tool for applying seal caps.

Another object is to provide a tool of the foregoing character which is so constructed that the 10 actuating pressure required to contract the skirt of the seal cap over and behind the beaded end of the closure neck or flange is materially reduced, whereby the cap may be securely applied in seal-tight fashion without distorting the closure structure or the container wall.

A further object is to provide a tool for applying seal caps which includes but few parts, which parts are so constructed and arranged that wear is reduced to the minimum and ease in operation 20 is assured.

Still another object is to provide a tool embodying the foregoing features which is simple in construction, is strong and durable, may be assembled and disassembled easily and quickly, and 25 which is substantially foolproof in operation, whereby the ordinary unskilled workman may apply successive seal caps in a uniform seal-tight fashion.

A more specific object is to provide a tool of the 30 foregoing character which comprises an improved jaw unit including a disk-like supporting member and a plurality of annularly disposed arcuate jaw members supported thereby and adapted to engage and contract the skirt of the seal cap, the arrangement being such that the jaw members have a line-contact engagement with the supporting disk substantially throughout their width and about which they rock in their contracting and expanding movements.

Other objects and advantages, some of which lie in the form and relationship of the tool parts, will become apparent as this description progresses and by reference to the drawings wherein—

Figure 1 is a vertical sectional view of one form 45 of tool embodying my invention, the tool being shown in its expanded form ready for securing a seal cap in place;

Fig. 2 is a horizontal section taken substantially 50 on line 2—2 of Fig. 1;

Fig. 3 is another vertical sectional view taken at substantially right angles to Fig. 1, and the tool is shown with its parts in contracted condition with a seal cap secured in place;

Fig. 4 is a detached, perspective view of one

of the jaw members of the jaw unit shown in the previous figures;

Fig. 5 is an enlarged fragmental section taken substantially on line 5—5 of Fig. 3; and

Fig. 6 is an enlarged fragmental section taken 5 substantially on line 6—6 of Fig. 1.

The tool shown in the drawings is well adapted for applying seal caps to the filling and/or discharge openings of containers used for shipping and storing gasoline, oil, and the like, products. 10 It is to be understood, however, that tools embodying my invention have utility in any other instance where similar conditions of use are to be met.

With particular reference to the drawings, the 15 container illustrated includes a comparatively thin wall 15 (Figs. 1 and 3) having a circular and outwardly-extending flange 16 defining a fill and/or discharge opening. An internally threaded bushing 17 (Fig. 1) is mounted within the 20 flange 16 and its outer end is turned over and upon the outer edge of the flange 16 providing a bead 18 thereat. A closure plug (not shown) is usually screwed into the bushing 17 for primarily closing and sealing the opening. The closure 25 structure just described is further closed and sealed, so as to guard against leakage and undetectable tampering, by a cap 19 having a skirt portion 19a contracted over the bead 18 and upon the flange 16 therebehind. It is essential, in applying the seal cap 19, that distortion of the container wall 15 and the closure structure as a 30 whole be avoided, otherwise leakage may occur.

My invention takes care of the condition last stated by providing an improved tool which is 35 adapted to apply the seal cap without the exertion of pressure in axial direction sufficient to cause distortion of the thin-walled parts, the arrangement of the tool parts being such that the operating pressure required to contract the skirt 40 19a of the cap is materially reduced below that required in tools heretofore employed. This reduction in operating pressure is brought about by reducing to a minimum the contact between the mounting means of the jaws and the body member 45 of the tool. In this manner friction and binding of the mounting is substantially eliminated allowing for adequate radial pressure for sealing while keeping down the axial, or downward force.

Specifically, the tool illustrated includes a central stem-like body member 20 (Figs. 1 and 3) rotatably supporting a novel jaw unit 21 including a plurality of expandable and contractible jaw members generally shown at 22 which are adapted 50 55

to be simultaneously actuated to similar extent by a bell-shaped jaw-operating member 23 surrounding the jaw unit. The body member 20 also rotatably supports an inverted cup-shaped centering head 24 which is surrounded by the jaw unit 21, and which with the jaw unit is confined against axial displacement by an enlarged head 25 on the lower end of the body member 20 and a detachable spring ring 26 mounted in a suitably provided groove in the body member 20. The body member 20 further supports a handle-mounting member 27 to which the inner ends of handles 28 are pivotally connected by pins 28^a. The inner ends of the handles 28, adjacent the pivot pins 28^a, are also connected to the jaw-operating member 23 by suitably provided links 29 and 30 so that downward movement of the outer ends of the handles 28 will result in downward movement of the jaw-operating member 23 and, in turn, contraction of the jaw members 22. Raising of the handles 28 will raise the jaw-operating member 23 and permit expansion of the jaw members 22 in a manner that will become obvious hereinafter. The handles 28, their mode of support by the body member 20, and their manner of connection with the jaw-operating member 23 are fully disclosed in my prior Patent No. 2,034,776, granted on March 24, 1936, and it will, therefore, be unnecessary to further describe the same in detail herein.

The jaw unit 21 and the parts thereof are so constructed and arranged that the pressure required to move the jaw members 22 inwardly to fully contract the skirt 19^a of the seal cap (Fig. 3) is reduced to the minimum. This feature not only avoids distortion of the container wall 15 and the closure structure as a whole, but it also reduces wear so that the tool will serve its purpose efficiently over a long period of time. Specifically, the jaw unit 21 (Figs. 1 and 3) includes a disk-like member 31 rotatably supported by the body member 20, between the centering head 24 and spring ring 26 and having an annular groove 31^a of substantially rectangular shape in cross section in its peripheral edge. The disk 31 supports the jaw members 22 each of which is of identical size and is of transverse arcuate shape with its side edges tapering radially inward so that when all of the jaw members 22 are arranged in annular fashion and contracted they will fit snugly together along their side edges forming a substantially complete circle.

The jaw members 22 are supported by the disk 31 in the following manner (Figs. 1, 3-6): Each 55 of the jaw members 22 has a lower or skirt portion 22^a. The upper boundary of the skirt portion is established by a chord-like land or ledge 32 which projects inwardly from the inner surface of the body member and extends substantially throughout the width of the same. This ledge 32 is of such width that it is adapted to fit rather snugly within the peripheral disk groove 31^a and the lower projecting corner 33 of this ledge (Fig. 4) is squared away in such a manner 60 that it engages the lower side 31^b of the disk groove 31^a along a line contact 34 (Figs. 1 and 3) extending substantially tangentially to the bottom 31^c of the groove 31^a (Figs. 1, 5 and 6). The upper edge of the ledge 32 is counter-cut as at 65 35 and the disk 31 above the groove 31^a is reduced in diameter so that the upper end of the jaw member (above the groove 31^a) may rock inwardly toward the disk 31 even though the ledge 32 may fit rather snugly within the groove 31^a.

70 75 The upper ends of the jaw members 22 are

urged radially inward and they are also normally held pressed together in circumferential direction as a self-contained unit by a spring ring 36 confined in a groove 37 in the outer upper end portions of the jaw members. The spring ring 36 also holds the jaw member ledges 32 engaged within the disk groove 31^a with the lower outer corners of the ledges 32 engaging the lower side of the groove along the line contact 34 about which the jaw members 22 rock during their expanding and contracting movements. The spring ring 36 constantly urges the jaw members toward an expanded position, and the limit of expansion of the jaw members is preferably determined by the jaw-operating member 23. The uppermost 15 position of the member 23, and the extent of expansion of the jaw members 22, may be adjustably determined by the position of the handle-supporting member 27 upon the threaded end 39 of the body member 20, and this uppermost position 20 is preferably such that the bell member 23 determines the extent of expansion of the jaw members, independently of any stopping action afforded by the engagement with each other of the upper ends of the jaw members 22 when the skirt 25 portions 22^a thereof are in their fully expanded condition. In this way, the limit of expansion of the tool may be definitely fixed and slight manufacturing variations in the jaw members and associated parts will not affect the operation of the 30 tool.

The lower or jaw ends 38 of the jaw members 22 are provided with inwardly-extending ledges 40 providing jaw faces adapted, upon contraction of the jaws, to engage the side wall or skirt 19^a 35 of the seal cap 19. The tool as a whole is centered in the proper position upon the cap 19 by the centering head 24 which is provided with a squared rim portion 41 adapted to seat upon the peripheral edge portion of the cap 19, which peripheral edge portion may, in some cases (as shown), be offset.

In the operation of the tool, the seal cap 19 is first applied over the closure structure, preferably, with a gasket 42 (Fig. 1) disposed between 45 its inner peripheral edge portion and the top of the bead 18. The tool is then placed in the position shown in Fig. 1, and the outer ends of the handles 28 are moved downwardly, in turn moving the member 23 downwardly causing the jaw 50 members 22 to rock about their line contacts 34 and move the lower or jaw faces 40 of the jaw members 22 inwardly to engage and contract the skirt 19^a of the cap 19 as shown in Fig. 3. Due to the fact that the jaw members 22 rock about a 55 line contact with a minimum of friction, the pressure required to move the handles 28 downward and contract the cap skirt is materially reduced. The line contact 34 may shift very slightly during this action, but, if so, the action is negligible 60 so far as the foregoing results are concerned. As the jaw members 22 are simultaneously rocked and contracted to similar extent by the member 23, the lower ends of the jaw members move together with a uniform circumferential contracting movement and, in their finally contracted position (Fig. 3), the lower edges of the jaw members substantially abut each other at their sides. In this operation the skirt of the seal cap 19 is completely and uniformly contracted over and 70 behind the bead 18 and the cap 19 is depressed and secured in such a way as to provide a closure which is not only air and liquid-tight, but it is also proof against undetectable tampering. When the cap 19 is fully applied, the handles 28 75

may be raised, in turn raising the member 23 and permitting the spring 38 to expand the jaw members to the position of Fig. 1.

It is believed that the objects and advantages of my invention above first stated will be obvious from the foregoing description. The tool is quite simple in construction and it is composed of a minimum number of parts which may be constructed quite inexpensively. A tool embodying my invention is substantially foolproof and may be operated even by unskilled workmen without danger of distorting the container wall which, if it should occur, might result in leakage.

It is to be understood that, although I have shown only one form of tool embodying my invention, other changes in details and arrangements of parts may be resorted to without departing from the spirit and scope of my invention as defined by the claims that follow.

20 I claim:

1. In a tool of the class described, a body member, a jaw supporting member thereon, a plurality of jaw members, means providing a line contact engagement between said supporting member and said jaw members and about which said jaw members rock for expansion and contraction movements, means engaging said jaw members on one side of said line contact means and constantly tending to expand said jaw members, and means 25 engaging said jaw members on the other side of said line contact means and operable to contract said jaw members in opposition to said first means.

2. In a tool of the class described, a body member, a jaw supporting disk carried by said body, a plurality of jaw members of transverse arcuate shape annularly fitted around the periphery of said disk, line-contact means between each of said jaw members and said disk and about which said 40 jaw members rock in expanding and contracting, means constantly tending to expand said jaw members, and means carried by said body and operable to contract said jaw members in opposition to said expanding means.

45 3. In a tool of the class described, a body member, a circular jaw supporting member carried by said body member, a plurality of jaw members each having a skirt portion of transverse arcuate shape fitting around the periphery of said jaw supporting member, means for supporting said jaw members on said jaw supporting member including a lateral chord-like element on each said jaw member having a straight edge adapted to engage said supporting member along a line contact about which said jaw members rock, spring means 50 engaging said jaw members constantly urging said skirt portions about said line contact toward an expanded position, and means carried by said body member for contracting said skirt portions in opposition to said spring means.

60 4. In a tool of the class described, a body member, a jaw supporting disk carried by said body member and having a continuous circumferential groove in its peripheral edge, a plurality of jaw members each having a skirt portion of transverse arcuate shape annularly arranged around said disk with each of said jaw members having a chord-like land or ledge of rectangular shape in cross-section extending substantially throughout the width of the jaw member and received within said disk groove, said ledge having a squared corner adapted to engage one of the surfaces of said groove along a line contact about which said jaw members rock in expanding and contracting, means engaging said jaw members

on one side of said line contact and constantly tending to expand said jaw members, and means engaging said jaw members on the other side of said line contact and operable to contract said jaw members in opposition to said spring means.

5. In a tool for applying seal caps, a body member; a disk-shaped jaw supporting member carried by said body member; a plurality of jaw members of arcuate shape transversely of their length; means for mounting said jaw members on said disk-shaped member, with a part thereof projecting above said disk-shaped member, and including a chord-like land or ledge of rectangular cross-section intermediate the ends of each said jaw member, a continuous and rectangularly-shaped groove in the peripheral edge of said disk-shaped member in which said chord-like ledge is received, and spring means engaging said parts of said jaw members above said disk-shaped member and tending to rock said jaw members upon their said ledges in expanding direction; and means carried by said body member and operable to move said jaw members in contracting direction.

20 6. In a tool for applying seal caps, a body member, a disk-shaped member carried by said body member and having a continuous rectangularly-shaped groove in its peripheral edge, a plurality of jaw members of arcuate shape transversely of their length and each having a transverse chord-like element intermediate its ends entering said groove and engaging a side surface thereof along a line contact, said chord-like element projecting from said jaw member sufficiently for it to enter and engage said groove substantially throughout the entire width of each of the jaw members, spring means engaging said jaw members at one end and constantly urging said jaw members in expanding direction about said line contact, said groove-and-element relationship together with said spring means serving to hold said disk-shaped member and jaw members assembled as a self-contained unit independently of other supporting devices, and means carried by said body member and operable to move said jaw members about said line-contact in contracting direction.

25 7. In a tool for applying seal caps, a body member, a disk-shaped member carried by said body member and having a continuous groove in its peripheral edge, a plurality of jaw members of arcuate shape transversely, each of said jaw members having a chord-like ledge extending substantially throughout the width of the jaw members and received in said groove in substantially tangential relation to the bottom of the latter, said ledge having its lower corner squared so that its lower corner engages the lower side wall of said groove along a line contact about which said jaw member rocks in expanding and contracting movements of its lower end, means engaging the upper ends of said jaw members and tending to rock the lower ends of said jaw members about said line contacts in an expanding direction, and means operable to move the lower ends of said jaw members about their line contacts in contracting direction.

30 8. In a tool for applying seal caps, a body member, a disk-shaped member carried by said body member and having a continuous groove in its peripheral edge, a plurality of jaw members of arcuate shape transversely, each of which jaw members has a chord-like ledge received in said groove in substantially tangential relation to the bottom of the latter, said ledge being so shaped that its lower corner engages the lower side wall

of said groove along a line contact, and said ledge, disk-shaped member and jaw member being so relatively shaped as to permit endwise rocking movement of each of said jaw members about said line contact, spring means engaging said jaw members above said line contacts and constantly tending to rock said jaw members about their line contacts in an expanding direction, said spring

means and groove-and-ledge relationship serving to hold said jaw members operatively connected to said disk-shaped member, and means engaging said jaw members below their said line contacts and operable to rock said jaw members about their line contacts in a contracting direction.

JOHN W. SHERA.
